Primary Examiner — Cynthia M. Chin

(57) **CLAIM**

I claim the ornamental design for a construction toy, as shown and described.

DESCRIPTION

FIG. 1 is a perspective view of a construction toy showing my new design;

FIG. 2 is left-side view of the construction toy as shown in FIG. 1;

FIG. 3 is front-back view of the construction toy as shown in FIG. 1;

FIG. 4 is right-side view of the construction toy as shown in FIG. 1;

FIG. 5 is bottom view of the construction toy as shown in FIG. 1; and,

FIG. 6 is a top view of the construction toy as shown in FIG. 1;

No particular colour scheme forms part of the claimed design.
